KEY DECODER

John W. Fitzgerald, Milwaukee, Wis., assignor
to Briggs & Stratton Corporation, Milwaukee,
Wis., a corporation of Delaware

Application May 13, 1935, Serial No. 21,280

4 Claims. (Cl. 33—174)

This invention relates to improvements in key decoders and has as an object to provide a simple and effective device for checking or decoding the combination of a key.

More specifically it is an object of this invention to provide means for checking or decoding the combination of keys cut as described in the co-pending application of Raymond W. Griffith, Serial No. 15,269, filed April 8, 1935.

With the above and other objects in view which will appear as the description proceeds, this invention resides in the novel construction, combination and arrangement of parts substantially as hereinafter described and more particularly defined by the appended claims, it being understood that such changes in the precise embodiment of the hereindisclosed invention may be made as come within the scope of the claims.

The accompanying drawing illustrates one complete example of the physical embodiment of the invention constructed according to the best mode so far devised for the practical application of the principles thereof, and in which:

Figure 1 is a view in side elevation showing the complete decoder and its manner of use, parts thereof being broken away;

Figure 2 is a cross section view taken through Figure 1 on the plane of the line 2—2; and

Figure 3 is an enlarged fragmentary detail view.

As defined in detail in the aforesaid co-pending application, the locks with which this invention and said co-pending application are concerned, have their code combinations designated by numerals and letters. The numerals 1 to 6, inclusive, refer to the positions of the tumblers in the cylinder, and the letters C, B, N and Y, designating the colors copper, black, nickel and yellow, refer to the depth of the key engaging portions of the tumblers.

Assuming that a cylinder has the combination—

1—2—3—4—5—6
N—C—B—C—Y—B

a key to fit this combination is easily cut by means of the key cutting fixture forming the subject matter of the aforesaid co-pending application. To check the correctness of the key as cut is the purpose of this invention. Of course, it may also be used to ascertain the combination of any key already cut for purposes of duplication or the fitting of a lock cylinder thereto.

Referring now more particularly to the accompanying drawing, in which like numerals indicate like parts throughout the several views, it will be seen that the device consists of a body 5 which may take the form of a conventional cylinder, as shown, provided with a keyway 6 into which a key 7 to be decoded is insertable. As in a conventional lock cylinder, tumblers 8 are mounted in the body 5 with their key engaging portions 9 accessible from the keyway 6 to be engaged by the blade 10 of the key.

Each tumbler has an individual spring 11 pressing it down into its respective pocket so that upon the insertion of the key, the tumblers are lifted against the action of their springs. All of the springs are conveniently held in place by a plate 12 having an angular extension 13 received in a slot 14 cut into the body 5 and held therein by a rivet 15. As shown, the plate 12 extends longitudinally across the tumbler receiving pockets of the body 5 in position to be engaged by the outer ends of all of the springs.

The plate 12 forms substantially a fin extending radially from the top of the body 5 in line with the motion of the tumblers imparted thereto by the key. The tumblers are provided with upward extensions 16 which overlie the front of the plate 12 to move up over the plate to heights determined by the contour of the key. The plate 12 may have indicia formed directly on its front face cooperable with the projecting ends 16 of the tumblers to enable the combination of the key to be visually depicted, or as in the present instance, a separate indicator plate 17 having such indicia may be secured to the front face of the plate 12. In any event, there are four superimposed stripes 18, 19, 20 and 21 paralleling the axis of the body and so disposed that the projecting tumbler ends 16 are lifted to align with these stripes upon insertion of the key.

The stripes 18, 19, 20 and 21 are respectively colored yellow, black, nickel and copper and to one side the letter designations Y, B, N and C are also delineated on the plate 17, preferably in their respective colors with lead lines connecting the letter designations with their respective stripes 18, 19, 20 and 21.

Above the stripes and in line with the tumblers are the numerical designations 1, 2, 3, 4, 5 and 6, representing the different positions of the tumblers in the lock.

As will be readily apparent, to use the device it is only necessary to insert the key into the

- keyway. The serrated edge of the key then moves the tumblers to heights determined by the contour of the key, the degree of motion being indicated by the projecting upper ends 16 of the tumblers moving into register with the stripes 18, 19, 20 and 21. The entire combination is thus visually depicted by the location of the upper ends of the tumblers with respect to these stripes.
- 10 What I claim as my invention is:
1. A key decoding device comprising a body having a keyway adapted to receive a key, spring pressed tumblers mounted in the body and adapted to be lifted to different heights against the action of their springs by a key inserted into the keyway, end portions on the tumblers projectible from the body to heights corresponding to the distances the tumblers are lifted by the key, a part carried by the body and having a surface across which the projecting end portions of the tumblers move, and side by side stripes representing different tumbler depths delineated on said surface transversely across the paths of the tumbler end portions to cooperate therewith and indicate the combination of the key.
  2. A key decoder of the character described comprising a body having a keyway into which a key to be decoded is insertable, tumblers movable in the body by a key inserted into the keyway, indicating portions forming an integral part of the tumblers projectible from the body, an indicator plate carried by the body and disposed in a plane parallel to the motion of the tumblers and so disposed that the indicating portions of the tumblers move across said plate, and indicia on the plate cooperable directly with the indicating portions of the tumblers to depict the combination of a key inserted into the keyway.
  3. A key decoder of the character described

comprising a body having a keyway to receive a key to be decoded, a plurality of tumblers mounted in the body and movable by a key inserted into the keyway, springs for the tumblers to yieldingly maintain the tumblers in predetermined positions from which they are moved by the key, a plate carried by the body and having a portion forming an abutment for the springs to hold the springs and tumblers in the body, said plate being disposed in the plane of movement of the tumblers, indicating portions on the tumblers movable across said plate, and indicia on the plate cooperable with the indicating portions of the tumblers to indicate the different heights to which the tumblers are moved by a key inserted into the keyway so that the combination of the key is determinable by the position of the indicating portions with respect to said indicia.

4. A key decoder of the character described comprising a body having a keyway to receive a key to be decoded, a plurality of tumblers mounted in the body and movable by a key inserted in the keyway, said tumblers having a stepped end portion part of which projects from the body, a spring engaging the step of each tumbler to yieldingly maintain the same in a predetermined position from which it is moved by the key, a plate carried by the body in line with the stepped ends of the tumblers with one edge engaging the springs to hold the same and the tumblers in the body, said plate being so disposed that said projecting parts of the tumblers move flatwise thereacross, and a plurality of indicating lines delineated on the plate across the paths of said tumbler parts to cooperate therewith and indicate the different heights to which the tumblers are moved by a key inserted into the keyway.
